UNITED STATES PATENT OFFICE.

JERRY H. BESAW, OF HUNTINGTON, MASSACHUSETTS.

CHAIN CONNECTOR.

Application filed March 24, 1922. Serial No. 546,459.

To all whom it may concern:

Be it known that I, JERRY H. BESAW, a citizen of the United States of America, and a resident of Huntington, in the county 5 of Hampshire and State of Massachusetts, have invented a new and useful Chain Connector, of which the following is a specification.

My invention relates to improvements in 10 devices designed for connecting the ends of chains, and consists essentially of two plates pivotally connected side by side and provided with two pairs of recessed jaws, all 15 of peculiar construction, and as hereinafter set forth.

The primary object of my invention is to provide a device of this character which can readily be pivotally connected with one end 20 of a chain, and is capable of having securely attached thereto the other end of such chain, such device being simple in construction 25 and operation, strong and durable, and so safe and reliable as to be free from liability of becoming accidentally disengaged from the chain.

This connector is especially adapted for use with anti-skid chains for motor-driven vehicle tires.

Other objects and advantages will appear 30 in the course of the following description.

I attain the objects and secure the advantages of my invention by the means illustrated in the accompanying drawings, in which—

35 Figure 1 is a side elevation of a chain connector which embodies a practical form of my invention, such connector being open; Fig. 2, a side elevation of said connector, showing the same closed, and having in engagement with its upper terminal a chain link, and, Fig. 3, an elevation of the parts and members shown in Fig. 2 as viewed from the right-hand side or edge thereof.

Similar reference characters designate 45 similar parts throughout the several views.

The connector comprises flat plates 1—1, each of which is provided at one end with a jaw 2, and intermediate of such end and the opposite end with a generally similar 50 jaw 3. The jaws 2 and 3 on each plate 1 form a slot 4, and such jaw 3 with that portion of said plate which constitutes a heel 5 form a slot 6. The inner end of each slot 4 is concave as shown at 7, and so also is the inner end of each slot 6. Each slot 4, furthermore, has upwardly-and

downwardly-extending extensions which form two notches or recesses 8, and there are similar notches or recesses formed by upwardly- and downwardly-extending portions of each slot 6. The recesses 8 are located at the inner terminals of the slots 4 and 6, at the ends of the concavities 7.

The plates 1 are designed to be placed side by side, with their heels 5 both at one 65 end and their jaws 2 both at the other end, and said heels are perforated to receive a pivot 9, which latter may consist of a member having a head at one end and the other end upset, or of any other suitable member or members.

A chain member, such as a clevis 10, is mounted on portions of the pivot 9 which project beyond the plates 1, and washers 11—11 may be introduced between the portions of the arms of said clevis that are on opposite sides of said plates and the enlarged, end portions of said pivot. By this or some other suitable means the connector plates are permanently but movably connected with a chain. A link at the end of the chain opposite to that to which the clevis 10 is attached, or which consists of such clevis, is represented at 12. The lower, free terminal portion of the link 12 is receivable in the slots 4 and the notches 7 which form parts of extensions of such slots, and is also receivable in the slots 6 and the notches 8 which form parts or extensions of said last-named slots.

The edges of the slots 4 and 6, outside of the notches 8 and the concavities 7, are in the form of arcs struck from the axial center of the pivot 9. The construction and arrangement of the plates 1, with their arcuate slots and the other concavities therein, are such that, when said plates are brought in complete parallelism, the free ends of the jaws 2 and 3 on either of said plates are in exact alignment with the unbroken longitudinal edge of the other of said plates, the two slots 4 are alongside of the plates, as are also the two slots 6, and the two upper concavities 7 and the two lower concavities 7 form central openings 13—13 completed above and below by the four pairs of notches 8, which notches in each pair are in alignment, all substantially as shown in Fig. 2. The lower, free terminal of the link 12 is receivable in either of the openings 13, and in any of the aligning notches 8. Due to the fact that the notches 8 in each

pair are in alignment when the connector is closed, the plates 1 are locked against outward movement on the pivot 9, by the link 12 when its free terminal is in such 5 notches.

In practice, when the plates 1 are swung or rocked outwardly on the pivot 9 to cause them to assume the open position, substantially as shown in Fig. 1, the lower, free 10 terminal of the link 12 is introduced into one or the other of the slots 4, or into the space between the open ends of such slots, and said plates are rocked inwardly on said pivot to cause them to assume the closed 15 position, substantially as shown in Figs. 2 and 3, the jaws 2 and 3 on one plate passing by the corresponding jaws on the other plate, into the last-named position. The lower terminal of the link 12 is now partly 20 in the uppermost, aligning notches 8 and partly in the upper opening 13, assuming that such link be under tension. When in this position the link 12 locks the plates 1 in their closed position, by reason of the 25 existing engagement between said link and the edges of the upper notches 8, so that it is practically impossible to rock said plates into open position so as to disengage and release said link. In the event of back pressure, or pressure downwardly according to 30 the position of the parts in the drawings, on the link 12, the free end of said link is thrust into the lower notches 8 which open into the slots 4, and as securely locks the 35 plates in closed position as was the case when said link was in the notches 8 above. On account of the concavities 7 at the inner ends of the slots 4, the interengaging end of the link 12 is invariably guided into the 40 notches 8, either those above or those below said concavities, accordingly as said link be drawn outwardly (upwardly) or forced inwardly (downwardly).

Upon opening the plates 1 wide enough to 45 enable the lower end of the link 12 to pass between the jaws 3, said end can be locked in place by said jaws when said plates are closed, the link end then being received either in the notches 8 at the top of the 50 slots 6 or in the notches 8 at the bottom of such slots, and being guided to such notches in practically the same manner as in the first example. The link 12 may be introduced beneath the jaws 3 in the first instance, or

may be introduced beneath the same for the 55 purpose of taking up slack in the chain, after having previously been held between the jaws 2 and 3.

From the foregoing it is apparent that this device, after being closed, is practically 60 self-locking, so that the link 12 is held with absolute security and safety.

To remove the link 12 from the connector, it is simply necessary to rock the plates 1 outwardly on the pivot 8 far enough to enable 65 said link to clear the jaws 2 or 3, as the case may be.

The plates 1 may be provided in their outer sides with indentations, as 14 for the insertion of the thumb and finger nails to 70 facilitate opening the device.

More or less change in the shape, size, construction, and arrangement of some or all of the parts of this connector, in addition to those of which particular mention 75 has been hereinbefore made, may be resorted to without departing from the spirit of my invention or exceeding the scope of what is claimed.

What I claim as my invention, and desire 80 to secure by Letters Patent, is—

1. In a chain connector, plates arranged side by side and pivotally connected at one terminal, said plates having registering jaws on oppositely-disposed edges, with registering slots between said jaws, the upper and under edges of which slots are in the form approximately of arcs struck from the axial center of the pivot, and the inner ends of which slots form upper and under 90 notches, said slots and notches being adapted to receive a link.

2. In a chain connector, plates arranged side by side and pivotally connected at one terminal, said plates having registering jaws on oppositely-disposed edges, with registering slots between said jaws, the upper and under edges of which slots are in the form approximately of arcs struck from the axial center of the pivot, and the inner ends of which slots are concave, and form upper and under notches separate from the concave portions, said slots, concave portions, and notches being adapted to receive a link.

JERRY H. BESAW.
